PULVERIZER

Peter C. Forrester, Tacoma, Wash., assignor to
Forrester-Largilliere Engineering & Milling
Company

Application April 14, 1933, Serial No. 666,166

5 Claims. (Cl. 83—9)

My invention relates to a pulverizer. More particularly, my invention relates to a pulverizing device for comminuting materials and has particular reference to providing vibrating means for the screens mounted on the pulverizer for screening the material after pulverization.

For purposes of clearness and illustration, I will describe my invention as applied to the pulverizing of mineral ores, but it is to be distinctly understood the same is not limited to any such specific application. It has also been found successfully applicable to pulverizing diatomaceous earth, cement rock, coal, coke, talc and also wood chips for the manufacture of wood pulp.

15 The present invention is an improvement upon the patent for the pulverizer granted to me in United States Letters Patent 1,142,159, bearing date of June 8, 1915.

20 In general, my device of said patent is distinguished from the usual ball or rod machine in that the rods are mounted in rings supported by spiders so that the machine is a balanced machine and requires much less power than is commonly employed in the ordinary ball or rod crushing machine wherein the ball or rods are located only in the bottom of the machine.

25 The rings in my former machine were rigidly mounted on the shaft on which the drum was mounted. In that machine the screen elements through which the pulverized material passes, in being discharged from the machine, tend to clog.

30 A primary object of my present invention is to provide means for causing said screens to vibrate and also to cause the rod rings to vibrate whereby the screens are maintained clean, and therefore, in a condition to be highly efficient. Also by imparting vibration to the screens I provide for a much longer life for said screens. Furthermore, in providing for vibrations for the machine in operation to be imparted to the rod and mounting rings, I provide for a greatly increased efficiency in the pulverizing action of the rods in that a hammer action is imparted to them as well as a rolling, crushing action with respect to the material.

35 The above mentioned general objects of my invention, together with others inherent in the same, are attained by the device illustrated in the following drawings, the same being preferred exemplary forms of embodiment of my invention, throughout which drawings like reference numerals indicate like parts:

40 Figure 1 is a view in perspective of the machine

embodimenting my invention, with parts broken away;

Fig. 2 is a view in cross section of the machine embodying my invention;

Fig. 3 is an enlarged view of the rod and screen mounting;

Fig. 4 is a view in perspective of the preferred form of screen holder;

Fig. 5 is a view in perspective of the screen frame;

Fig. 6 is a view in perspective of the central hollow feed drum shaft element of my invention;

Fig. 7 is a view in cross section of a modified form of the screen means formed by combining a fine screen and a coarse screen;

Fig. 8 is a fragmentary view in perspective of said modified form of screen means;

Fig. 9 is a fragmentary cross sectional view of a modified form of my invention showing the screen mounted directly upon the longitudinal beam on which beams are mounted the rod rings;

Fig. 10 is a fragmentary cross sectional view of still a further modified form of a pulverizer embodying my invention;

Fig. 11 is a separate view of the drum opening closing means which may have varying size openings to accommodate material of different character as may be desired and thereby the distribution of the material regulated with respect to the length of the drum.

45 A revolvable drum may be formed with end members 12 mounted on an axially disposed feed cylinder 13 with outlet openings 14 through which the material to be ground may be passed radially, and members 12 are joined by cross members 15 which are preferably in the form of flexible or resilient beams—wooden beams serving admirably for this purpose. A shell 16 also joins the end members 12, said shell having openings 17 over which screens 18 are mounted. Rods

19 are mounted in bundles in rings 20, and the rings 20 are mounted on the cross members 15 by lugs 21. Screens 18 are mounted in a rectangular supporting screen frame 22 (see Fig. 3),

45 having lateral members 23 with shelf 24 and medial members 25 with shelves 26. These shelves also extend across the end members of the frame. The screen supporting frames 22 are secured to shell 16 by bolts 27 passing through lateral members 23.

The screens 18 are releasably held against shelves 24 and 26 by frames 28, which in turn are releasably held in place by screen holders 29 having notches 30 and 31 to engage respectively bolt 27 and bolt 32. Bolt 33 passes

through cross member 15 and medial member 25 with a spacer sleeve 34 between cross member 15 and medial member 25.

Material elevating blades or flanges 35 are mounted on cross member 15 by bolts 33. These elevating flanges are preferably in spaced relation to the feed cylinders 13 so as to permit the material to pass from one to another of the chambers occupied by the bundles of rods 19.

10 In the modified form of screen shown in Figs. 7 and 8, a coarse screen 36 is mounted on inclined members 37, leaving opening 38 so that material which is fine enough to pass the coarse screen 36, but too coarse to pass fine screen 18, may fall back upon the bundles of rods 19 for further grinding.

15 In the modified form shown in Fig. 9 the screen supporting frames 39 are mounted directly upon cross members 40, which in this instance are located adjacent the shell 16.

20 In the modified form shown in Fig. 10 the cross members 41 are located adjacent the shell 16 and between adjacent screen supporting frames 42. Rings 43 are separately secured to said cross beams by means of bolts 44.

25 In Fig. 11, feed drum openings 17 are provided with reduction plates 45 which have smaller openings 46 than openings 14 in the feed drum, thereby material being fed into the drum may be distributed. That is, with these plates disposed over those openings 14 located in the end portion of the feed drum nearest the material feed spout 47, the material will be caused to be distributed more uniformly throughout the length of the drum.

30 The mode of operation of my invention is as follows:

35 The material is fed into the said cylinder 13, from which it escapes through openings 14 into the chambers in which are mounted the bundles of rods 19. The oversized material is retained by the rods 19 and gradually ground while the finer material sifts through the rods 19 and is further pulverized. Subsequently, the coarser material is reduced in size and is pulverized by the action of the rods. Any portion of the oversized parts of the material that escapes to the screen 18 is picked up by the elevator blades or flanges 35 and dropped upon, or returned to the various 40 bundles of rods. It will be noted that a given portion of the material is not confined to the action of any particular bundle or set of rods or rods 19, but that the material is exposed to any and all of the various sets of rollers.

45 It will be understood, depending of course upon the size of the mill, that there is ordinarily one-half ton of rods in each ring—each rod weighing from twenty-five to forty pounds. This is true for a mill forty-eight inches in length. Of course, said weight is greater in a longer mill.

50 The rolling and tumbling of this weight of rods in the rings 20 set up vibrations, and these vibrations are taken advantage of by mounting the rod rings on the cross members 15, said members being preferably of wood for treating ores so as to avoid crystallization and to provide resiliency. These cross members 15 are preferably mounted in the peripheral portion of the drum so as to depend and take advantage of all 55 the vibrations possible. The screen supporting members are preferably formed of wooden members in order to provide resiliency as the central mounting means of the screens 18. The screen supporting members are connected by a bolt and spacer sleeve 34 to the cross member 15. In this

wise the vibrations imparted to the cross members by the rods in the rings are transmitted directly to the screens 18 and maintain the same in constant vibration. By having the screens 18 continually in vibration they are maintained clean and in a more highly efficient condition for performing their function of screening the material. By maintaining the said screens 18 in a clean condition, also the life of the screen is greatly extended. Screens 18 may be readily replaced, whenever they do become worn, by merely disconnecting screen holder 29 and removing screen frame 28, which serves to clamp the lateral edge portions of screen 18 against the shelves 24 and 26.

10 In addition to the fine screen 18 a scalping or coarse screen 36 may be positioned inwardly of the fine screen 18. By having this screen 36 secured in closed position along the forward or advancing edge when the direction of the rotation 20 of the drum is considered and by having this coarse screen mounted on wedge or inclined members 37 with respect to the fine screen 18, an opening 38 is provided with respect to the following edge of the coarse screen 36. Thus, if material is of such degree of fineness that it may pass through the coarse screen 36, but is too coarse to pass through the fine screen 18, it will pass through the opening 37 and fall back upon the rods 19 for further pulverizing.

15 In this way I eliminate the common trouble where a coarse screen is employed in conjunction with a fine screen to give support to a fine screen and protect the same from having some portion of the material pass through the coarse screen 36 and becoming lodged against the fine screen 18. This material becomes packed in between the two screens and results in a clogging of both screens. By positioning the coarse screen 36 in spaced relation, and by having the opening 38, 25 as herein set forth, provision is made for the material that passes the coarse screen to be returned to the rods 19 for further pulverization.

20 From the above, it is manifest that I provide for setting up vibration in the screens 18 by taking advantage of the vibration set up by the grinding means, as well as by the vibration of the apparatus or mill as a whole to cause the screens to be kept in constant agitation and thereby kept clean. Thus, I utilize the inherent vibration of 30 the machine without any separate vibrating mechanism to make the screens 18 most efficient.

25 Also, I employ the said vibration to make the rods themselves more efficient in their operation by imparting a hammer-like action to said rods 35 in addition to their rolling action, while performing their pulverizing function.

30 Obviously, changes may be made in the forms, dimensions, and arrangement of the parts of my invention, without departing from the principle 40 thereof, the above setting forth only preferred forms of embodiment.

I claim:

35 1. A pulverizer embodying a central feed drum shaft having material discharge openings therein; end plates fixedly mounted on said drum shaft; flexible cross members extending parallel between the said end plates, said members being in spaced relation to said drum shaft; rod rings supported by and mounted between said cross 45 members; movable rods in said rings causing vibrations; screen supporting frames peripherally mounted for vibratory movement on said end plates; and means connecting said screen supporting frames to said cross members, whereby 50

the vibrations of said rings are transmitted to said screen supporting frame.

2. A pulverizer embodying a central hollow feed drum shaft having openings in its peripheral portions for material discharge outlets; plates fixedly mounted on said drum shaft; flexible vibratile means mounted in the peripheral portion of said end plates; vibrating rod rings mounted on said vibratile means; and screen means mounted 10 on said vibratile means, whereby the vibration of said vibrating rod rings are transmitted to said screen means.

3. A pulverizer embodying a central feed drum shaft having material discharge openings therein; end plates fixedly mounted on said drum shaft; flexible wooden cross members extending parallel between the said end plates, said members being in spaced relation to said drum shaft; rod rings supported by and mounted between said 15 cross members; movable rods in said rings causing vibrations; screen supporting frames peripherally mounted for vibratory movement on said end plates; and means connecting said screen

supporting frames to said cross members, whereby the vibrations of said rings are transmitted to said screen supporting frame.

4. A pulverizer embodying a drum; screens mounted for vibratory movement in said drum; vibratile cross members in said drum; grinding means in said drum supported by said vibratile cross members and causing vibrations; and means connecting said screens to said vibratile cross members, whereby the vibrations set up in vibratile cross members are communicated to said screens. 10

5. A pulverizer embodying screens mounted for vibratory movement in said drum; vibratile cross members in said drum; rod rings in said drum supported by said vibratile cross members; grinding rods supported by said rod rings and vibrating said rod rings and said vibratile cross members; and means connecting said screens and said vibratile cross members, whereby the vibrations 15 set up in said vibratile cross members are communicated to said screens. 20
